UNITED STATES PATENT OFFICE.

HENRY NOLAN, OF BROOKLYN, NEW YORK.

CABLE-GRIP.

1,114,637.

Specification of Letters Patent.

Patented Oct. 20, 1914.

Application filed July 30, 1913. Serial No. 782,152.

To all whom it may concern:

Be it known that I, HENRY NOLAN, a citizen of the United States of America, residing at Brooklyn, in the county of Kings 5 and State of New York, have invented new and useful Improvements in Cable-Grips, of which the following is a specification.

This invention relates to improvements in cable grips and has particular application to 10 a multiple grip.

In carrying out the present invention, it is my purpose to provide a cable grip whereby a plurality of cables or the like may be simultaneously drawn through a conduit 15 from a single pulling mechanism and which will be constructed in such manner that the loads on the various grips will be evenly distributed over the entire device.

It is also my purpose to provide a multiple grip device of the class described 20 wherein each grip will be formed of a number of strands of wire bent into spiral form and intersecting one another whereby the grip may be contracted and expanded to 25 facilitate the gripping action, and wherein a part of the strands of each grip will form an equal part of the strands of another grip, thereby enabling the loads on the various grips to be evenly and uniformly dis- 30 tributed over the entire device as a whole irrespective of the load or resistance on any one grip relatively to another or the other grips.

Furthermore, I aim to provide a device 35 of the type set forth which will embrace the desired features of simplicity, efficiency, durability and strength coupled with cheapness of cost in manufacture and marketing and which will automatically and ef- 40 fectively grip a cable.

With the above and other objects in view, the invention consists in the construction, combination and arrangement of parts hereinafter set forth in and falling within 45 the scope of the claims.

In the accompanying drawing; Figure 1 is a view in side elevation of a multiple grip constructed in accordance with the present invention. Fig. 2 is an enlarged 50 fragmentary view of one of the grips showing the construction thereof, and Fig. 3 is a diagrammatic view showing the manner of arranging the strands of wire to form the individual grips.

55 Referring now to the accompanying

drawing in detail, the numerals 1, 2 and 3 designate the individual grips of a multiple cable gripping device and these grips are formed of strands of wire arranged in such manner that a part of the strands of each grip form an equal part of the strands of another grip, thereby enabling the capacity of the device to be varied and the loads on the various grips to be evenly and uniformly distributed over the device as a unit. For instance, as illustrated in Fig. 3 of the drawing, one-half of the strands of wire forming the grip 1 have their opposite extremities arranged to form one-half of the grip 2, these strands being indicated 60 at A, while the strands forming the remaining half of the grip 1 and indicated at B have the free ends thereof arranged to form one-half of the grip 3. Coöperating with the ends of the strands A forming one-half of the grip 2, are strands C, the free end portions of the latter coöperating with the end portions of the strands B to complete the grip 3. Thus, it will be seen that the strands of wire A form one-half of the 65 grips 1 and 2, while the strands B form one-half of the grips 1 and 3, the strands C forming the remaining halves of the grips 2 and 3. By means of this arrangement of the strands, the loads on the grips are 70 evenly distributed over the entire device as will be readily understood.

In order to form the portions of the various wires constituting each grip into socket or grip formation, I interweave the respective portions in such manner that each individual wire is of spiral form and intersects every other wire. By means of this arrangement of the wires each grip may be expanded and contracted. Should the cable 75 end of larger diameter than the normal diameter of a particular grip, be inserted in such grip, such cable end will tend to expand the grip in the application of the latter to the former. However, when a pull is exerted upon the grip, the grip will contract, incident to the frictional engagement between the various strands thereof and the cable, thereby setting up a binding action 80 between the inner wall of the grip or socket and the cable. The intermediate portions of the wire strands forming the various grips are trained over an eye 4 and suitably secured thereto as by a cord 5. Sleeves 6 encircle groups of strands between the eye 85 90 95 100 105 110

4 and the grips so as to prevent abrasion between the strands when the grips 1 and 3 move toward the middle grip.

From the foregoing description taken in connection with the accompanying drawing, the construction, mode of operation and manner of employing my invention will be readily apparent.

Although I have shown and described a three grip device I wish it to be understood that any desired number of grips may be employed so that the capacity or range of the device may be varied.

I claim:

- 15 1. As a new article of manufacture, a cable gripping device comprising three grips formed of strands of wire woven into spiral form and intersecting each other, one-half of the strands of the first grip forming one-half of the second grip, the remaining half of the strands of the first grip

forming one-half of the third grip, one-half of the strands of the third grip forming the remaining half of the second grip, a loop formed intermediate of the ends of the 25 strands.

2. A cable gripping device comprising three grips formed of strands of wire woven into spiral form, one-half of the strands of one grip forming one-half of another 30 grip, the strands intermediate of their lengths being formed into a single eye, and sleeves encircling groups of strands adjacent the eye for preventing abrasion between the strands when the outer grips 35 move toward the middle grip.

In testimony whereof I affix my signature in presence of two witnesses,

HENRY NOLAN.
